UNITED STATES PATENT OFFICE

121,351

DESIGN FOR AN APPLIQUÉ MONOGRAM

Maria Rass, New York, N. Y.

Application March 23, 1940, Serial No. 91,197

Term of patent 3½ years

To all whom it may concern:

Be it known that I, Maria Rass, a citizen of the United States of America, residing in New York city, in the Borough of Manhattan, county and State of New York, have invented a new, original, and ornamental Design for an Appliquéd Monogram, of which the following is a specification, reference being had to the accompanying drawing, forming part thereof, wherein the figure is a plan view of an appliquéd monogram, substantially as shown.

I claim:

The ornamental design for an appliquéd monogram, substantially as shown.

MARIA RASS.
